UNITED STATES PATENT OFFICE.

CLARENCE CARSON SMITH, OF CAMPTOWN, PENNSYLVANIA.

BAGGAGE-CHECK.

SPECIFICATION forming part of Letters Patent No. 297,860, dated April 29, 1884.

Application filed March 7, 1884. (No model.)

To all whom it may concern:

Be it known that I, CLARENCE C. SMITH, a citizen of the United States, and a resident of Camptown, in the county of Bradford and State of Pennsylvania, have invented certain new and useful Improvements in Baggage-Checks; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of my improved changeable baggage-check. Fig. 2 is a similar view of the rotary disk removed. Fig. 3 is a longitudinal section through line $x-x$, showing the strap inserted in place; and Fig. 4 is a sectional view through the line $y-y$ in Fig. 3.

Similar letters of reference indicate corresponding parts in all the figures.

My invention has relation to that class of baggage-checks which are adapted to be changed so as to be used for a number of different stations; and it consists in the construction and combination of parts of the changeable baggage-check, which will be hereinafter more fully described and claimed.

In the accompanying drawings, A is a circular disk, of brass or any other suitable material, having a series of equidistant notches, a , in its periphery. Inserted through the center of the disk is a pin, B, the projecting ends of which are inserted through oblong slots, C, in parallel side plates, D, which are connected to each other at opposite ends by plates E, which are cut so as to form lugs or projections G, adapted to engage the notches a in disk A. Both of the side plates, D, have curved slots H, so arranged that a portion of the disk may be seen through said slots; and the disk is marked on both sides with the names of the stations on the road or roads on which the check is to be used, said names being arranged in curved spaces radiating from the center toward the periphery, and the name-spaces on one side of the disk alternating with, or breaking joints with, the name-spaces on the opposite side of the disk in the same manner as described in the specification forming part of another application filed by me for an improvement in changeable bag-

gage-checks, so that only one name will be exhibited in full through its appropriate name-slot H at a time, thereby obviating mistake or confusion in the use of the check. At opposite ends of the side plates, D, are slots I I, for the attachment of the strap J, by which the check is attached to the piece of baggage to be checked or marked.

From the foregoing description, taken in connection with the drawings, the manner of using my improved changeable baggage-check will readily be understood. After the disk has been turned in its oblong bearings C until the proper station-name appears in full through its appropriate slot, the disk is locked between the plates by pushing it up or down until one or more of the notches engage one or more of the fixed teeth G. By then inserting the double ends of the strap through the transverse slot I, at the opposite end of the plates, as shown in Fig. 3, the disk will be prevented from moving between the plates so as to disengage its notched periphery from the fixed teeth or projections with which it interlocks, thus holding the disk firmly in place. In order to change the name, the strap is withdrawn from its slot I, through which it is inserted, which permits the disk to be rotated until the new name is brought opposite to, and appears through its appropriate name-slot H, when the disk is again locked in place between the side plates in the manner described.

Having thus described my invention, I claim and desire to secure by Letters Patent of the United States—

The changeable baggage-check herein shown and described, consisting of the side plates having curved name-slots, strap-slots I I, and central oblong slots or bearings C, circular name-disk having center-pin B working in the slots C, and notches a , fixed teeth G, and strap or straps J, constructed and combined substantially as and for the purpose shown and set forth.

In testimony that I claim the foregoing as my own I have hereunto affixed my signature in presence of two witnesses.

CLARENCE CARSON SMITH.
